AUTOMATIC RADIO CONTROL

Roy P. Osborn and Leroy D. Hemman,
Laveen, Ariz.

Application June 27, 1939, Serial No. 281,474

9 Claims. (Cl. 161—1)

This invention relates to a device for automatically controlling a radio.

An object of the invention is the provision of a device which may be either incorporated in a radio, or which may be attached to a radio, the device being capable of being set for automatically tuning in any one of a number of stations consecutively and at predetermined times and for cutting off the radio after a particular broadcast has terminated, means being employed in connection with the clock mechanism for adjusting the timing mechanism and for resetting the clock mechanism and the timing mechanism.

Another object of the invention is the provision of a device for automatically tuning in a particular station at a predetermined time in which a belt having slits or other indicators moves over the dial in cooperation with a second belt having means thereon to close a circuit to one of a plurality of solenoids that in turn control the operation of the usual push buttons for automatic tuning or the mechanism connected to the buttons, the circuit to the solenoids or magnets being closed by a timing mechanism operated in conjunction with the mechanism for causing movement of the belt.

A further object of the invention is the provision of a device for automatically turning in and cutting off a particular station at a predetermined time, the timing mechanism being provided for the purpose in which a timer cooperates with other elements for closing a circuit to solenoids or magnets which operate the usual push buttons or a mechanism attached thereto of a well known automatic tuning, the timer being so constructed that every fifteen minutes it will close the circuit for the period of time necessary to operate the tuning mechanism and then leaves the circuit open for the remainder of the fifteen minute period, a plurality of discs being operated for causing a switch arm to contact with a switch element on a moving belt, each disc being marked to represent certain stations so that when the proper switch contacts a switch arm controlling the tuning circuit for a particular station that station will automatically come in, each disc representing a period of fifteen minutes so that when more than one disc is operated the time period may be increased accordingly.

The invention will be best understood from a consideration of the following detailed description, in view of the accompanying drawings forming a part of the specification, nevertheless, it is to be understood that the invention is not confined to the disclosure, being susceptible of such changes

and modifications as define no material departure from the salient features of the invention as expressed in the appended claims.

In the drawings:

Figure 1 is a fragmentary front view in elevation of the radio time control constructed according to the principles of our invention.

Figure 2 is a view in elevation of parts broken away showing the movable belt for aiding in controlling the closing of a plurality of circuits.

Figure 3 is a plan view partly in section of the radio control.

Figure 4 is a transverse vertical section taken along the line 4—4 of Figure 1.

Figure 5 is a vertical section taken along the line 5—5 of Figure 4.

Figure 6 is a transverse vertical section taken along the line 6—6 of Figure 5.

Figure 7 is a fragmentary vertical section through the operating gears shown in Figure 4.

Figure 8 is a front view of Figure 7 showing the timer arrangement.

Figure 9 shows more or less diagrammatically the circuits employed in connection with the radio control.

Figure 10 is a vertical section of a push button construction shown in Fig. 9.

Figure 11 shows more or less diagrammatically a modified form of the radio control.

Referring more particularly to the drawings, 10 designates a housing which may be independent of the radio which is to be automatically controlled by the mechanism contained therein, or the numeral 10 may represent the front panel of a casing of a radio when the control mechanism is built directly into the radio and forming part of the chassis. In either event the front panel of the housing or casing is provided with an illuminated section 11 which is graduated to indicate fifteen minute periods throughout the duration of twelve hours and this twelve hour period may represent either the forenoon or afternoon. The section 11 may be formed of glass or some transparent material having opaque lines.

At the rear of the section or window 11 is placed an annular belt 12 which is mounted on drums 13 and 14. The drum 14 is driven by a vertically disposed shaft 15 (Figs. 4 and 7) while the drum 13 is secured to the vertically disposed shaft 16 located in spaced relation with the driven shaft 15. Suitable bearings are provided for the shafts and one of these bearings is shown at 17 (Fig. 4). Each of the drums is provided with a plurality of teeth 18 at the opposite ends thereof and these teeth are adapted to engage perforations 19 in the

belt 12 so that when the drum 14 is revolved the belt will be moved in the direction indicated by the arrow in Figure 3 and the idler drum 13 is then revolved by the belt.

5 The shaft 15 is driven by a gear 20 and this gear is driven by a bevel gear 21 rotatably mounted on a shaft 22 and a gear 23 meshing with the gear 21 is driven by a shaft 24. The last-mentioned shaft is rotated by a clock mechanism generally indicated at 25 and this clock mechanism is of the usual electric type well known in the arts.

10 A belt 12a having the edges perforated similarly to the belt 12 is trained on the drum 14 and drums 13a and 14a are driven simultaneously with the belt 12 by the drum 14. One face of the belt 12a moves always in close association with the inner face of the panel 10 for a purpose which will be presently explained.

15 Collars 26 and 27 are located on opposite sides 20 of the gear 21 and are secured to the shaft 22 so that when said shaft is shifted, the gear 21 will be moved out of mesh with the gear 20 for a purpose which will be presently explained.

20 A bevel gear 30 (Fig. 7) is rotatably mounted 25 upon a sleeve 31 which is secured to a bracket 32 and this bracket is secured in any approved manner to the bottom of the housing 10. The gear 30 is provided with a hub portion 33 which is engaged by a collar 34 on the sleeve 31 while the inner 30 face of the gear is engaged by the bracket 32 for maintaining the gear in a predetermined position on the shaft 22. The collar 31 is held stationary as is the gear 30 when the shaft 22 is reciprocated.

25 At the outer face of the hub portion 33 of the gear 30 is formed a series of teeth 35 and a plurality of teeth 36 is formed on a collar 37 which is secured to an intermediate portion of the shaft 22 and the teeth 36 are adapted to engage the teeth 35 so that when the shaft is rotated manually to- 35

30 wards the right by a knob 38 the gear 30 may be 40 revolved in one direction. However, if the knob 38 were revolved in the opposite direction the teeth 36 would slide over the teeth 35 and thus prevent rotation of the gear 30. A coil spring 40a

45 39 embraces the shaft 22 between the pairs of teeth 35 and 36 and forces the shaft in the direction indicated by the arrow in Fig. 7 for maintaining the two groups of teeth out of engagement while maintaining the gear 21 in mesh with the gear 20.

50 When the knob 38 is moved in the direction indicated by the arrow in Fig. 4 and the clutch elements 35 and 36 will engage and the knob 38 is 55 revolved towards the right the gear 30 will be re- 60 volved as will be the gear 20 for rotating the shaft 15 to move the belts 12 and 12a in a direction for properly setting the belts so that one of the slits 40, 40a, 40b formed in the belt 12a will be properly aligned with one of the indicating lines on the dial 11. In other words, if the motor 25 would stop by reason of the current being cut off to the motor, the belts will then stop and it will be necessary to reset the belts to indicate the proper time since the member 11 takes the place of the usual dial of the clock.

65 A timer mechanism is shown more particularly in Figs. 7 and 8 and said timer mechanism consists of a ring 41 which is secured to the hub section 33 of the gear 30. The ring 41 is provided with a cam portion 42 and this cam portion is located outwardly of a ring gear 43. This ring gear is loosely mounted on the hub 33 and is adapted to be revolved independently of said hub.

70 75 This ring gear is held in place on the hub by means

of the ring 41 and a shoulder 44 which is formed between the hub 33 and the gear 30.

A spring switch arm 50 is secured at 51 to the outer face of the ring gear 43 and is insulated therefrom as shown at 52. A finger 53a is secured 5 to the spring member 50 and is adapted to ride over the periphery of the ring 41 so that when the cam member 42 engages the finger 53a the spring member 50 will be raised for separating the contacts 53 and 54 from each other to break the circuit. The contact 53 forms part of the spring member 50 while the contact 54 is secured to the outer face of the ring gear 43. The member 50 and likewise the contact 54 are connected by wires with a circuit as will be presently explained. The member 53 or the cam ring 42 may be formed of insulating material.

A spur gear 55 is secured to a shaft 56 and this shaft as shown in Fig. 3 extends through the front panel of the housing 10 and is provided with 20 a knob 58 located adjacent the knob 38.

It will be found that there are times when the ring gear 43 is so positioned that the cam member 42 will operate the spring arm 50 out of synchronism with the movement of the belts 12 and 25 12a and thus out of synchronism with the time-indicating element represented by a slit 40 or one of the slits 40a or 40b (Fig. 3).

The belt 12a which as has been explained is provided with a plurality of vertically disposed slits 30 40, 40a and 40b. Below each slit in said belt are a plurality of spring fingers 60, 61, 62, 63, and 63a in spaced parallel relation on the belt 12. Each of these fingers extend through the belt and are connected respectively to metal ribbons or conductors 64, 65, 66, 67 and 67a. These metal ribbons are secured to the inner face of the belt 12 in spaced parallel relation and are also spaced sufficiently apart so that they will be substantially insulated from each other (Fig. 2).

40 Figs. 1, 3, 5 and 6 show a plurality of discs 70 located in juxtaposition upon a shaft and to the periphery of each disc is secured a ring 71. It will be noted that the inner portions of the discs are cut away as shown at 72 and the rings are likewise cut off in the same manner. The ring 71 may be of insulating material, while the discs 70 are formed of a conducting material. An arm 73 extends inwardly from each disc and is of sufficient length so that when each disc is rotated the free end of the arm will move over one of the spring contact fingers 60 to 63a, inclusive. The arm also is shown in Fig. 6 as being in engagement with the spring finger 61 and this connection aids in closing a circuit which will be presently explained. All of the discs are rotatably mounted upon a shaft 75 which is secured at its opposite ends by the members 76 and these members are connected to the front panel 10a of the housing 10.

60 The discs are spaced from each other by means of thin spring plates 77 which are mounted in pairs on the shaft 75 between each pair of the discs 70. The outer bowed faces of the discs are provided with projections 78 which are adapted 65 to engage within pockets 79 formed in the faces of the discs. A key slot 80 formed in the shaft 75 is adapted to receive a projection 81 extending inwardly from the inner periphery of the central opening formed in each plate 77. The slot 80 and 70 the fingers 81 retain the plates 77 against rotation when the discs 70 are rocked. It will be seen by this construction that each disc 70 may be rocked in opposite directions so that the arm 73 may be placed at various horizontal positions for 75

engaging any one of the spring fingers 60 to 63a, inclusive.

As shown more particularly in Figs. 4 and 9, the shaft 75 is connected by a wire 54a with the contact 54. A plurality of brushes 83, 84, 85, 86 and 86a (Figs. 2 and 3) are fixed in position adjacent the inner front face of the belt 12 and these wipe along the respective ribbons 64 to 67a, inclusive. These stationary brushes are respectively connected with magnets 89, 90, 91, 92 and 93. The magnets are also connected by means of a wire 94 which forms part of the line of a low energy current. A wire 95 is connected to the spring arm 50 (Fig. 9).

15 A plurality of solenoids 89a, 90a, 91a, 92a and 93a are employed in connection with a plurality of push buttons B, B', B2, B3 and B4. Each solenoid, as shown more particularly in Fig. 10, has a movable core 96 to which is connected a 20 rod 97. A knob 98 of insulating material is connected to the inner free end of the rod beyond the solenoid and is adapted to engage a switch-actuating member 98a for one of the switches 99a, 99b, 99c and 99d. The switches 99a to 99d, 25 inclusive, are of the usual type and are adapted to be pushed in for automatically tuning in a particular station and any number of these buttons may be employed for the purpose. The arrangement is such in the radio that when one switch 30 is pushed in, any other switch which may have been pushed in for tuning some other station will be released for changing from one station to another. It will be seen that when any one of the solenoids is energized the core 96 will be drawn 35 inwardly so that the member 98 will press against one of the members to close one of the switches for tuning in a particular station. While I have shown five solenoids, it will be appreciated that any number of solenoids with the corresponding 40 number of metal bands 64 to 67a may be employed for the purpose. The switch 99 controls the radio power circuit and operates to open the circuit when pushed in and close the circuit when out. Thus if the radio is off and one of the switches 45 99a to 99d is pushed in to tune a station, 99 is released and turns on the radio power.

Each of the outer surfaces of the rings 11 are provided with a plurality of colored strips as shown in Fig. 6 and as indicated at 101, 102, 103, 50 104, and a dark strip 105. The various colors represent a particular station which is adapted to be tuned in locally. The black or dark strip 105 will indicate that the radio power is off when this strip is located at a horizontal position or in 55 a position opposite an indicator 106, Fig. 6, since the arms 13 will be in contact with finger 63a which controls button B and turns off the radio power. The indicator 106 is placed on the panel 10a. On some portion on the dial of the front 60 panel of the housing 10 is placed constructions in which each color is indicated as representing a particular station in a locality. When the proper color is placed in the horizontal position in line with the indicator 106, that particular station will 65 be tuned in because the arm 13 will engage a spring finger which in connection with the arm 13 closes the circuit to the proper solenoid 99a to 99d, inclusive, for operating one of the members 98 as will be presently explained.

70 Referring more particularly to Fig. 9, wires 108 to 113, inclusive, are connected between the respective contacts 83 to 86a, inclusive, and respective solenoids 89 to 93, inclusive. Wires 114 connect these magnets with the wire 94 and wires 75 94 and 95, as has been explained, are connected

with the low energy current of the radio. Due to the fact that the conductors 64 to 67a must be made of thin material, it is advisable only to use a low current in connection with the conductor. A manually operated switch 115 is employed for 5 opening or closing said low current circuit.

Wires 116 connect each of the solenoids 90a to 93a with the wire 88 which is directly connected to the solenoid 89a.

Outlet wires 117 lead from said solenoid to 10 respective switch points 118. A plurality of switches 119 to 123, inclusive, are operated by the magnets 89 to 93, inclusive, closing a circuit carrying a high energy circuit and represented by the 15 wires 88 and 88a.

The contacts 126 are connected with wires which control the usual mechanism in a radio for bringing in the station automatically.

The operation of my device is as follows: The timing control mechanism may be built directly 20 into the radio whereby the solenoids 90a to 93a, inclusive, in connection with the magnets 90 to 93, inclusive, will cause a station to be brought in at predetermined times and be maintained in operation for a predetermined time when one or 25 more of the members 70 are properly positioned whereby the arm 13 will be engaged by one of the movable contacts 60 to 63, inclusive. It will be appreciated that the timing mechanism is operating continuously as a clock whether the 30 radio has been turned on or off by the usual switch for the purpose.

The station is first selected and then one of the members 70 is rocked until one of the colored sections 101 to 104 inclusive, is aligned with the 35 indicator 106 on the dial. The member 70 which is operated must be one which will bring in that particular station at a particular moment and which is opposite one of the graduations on the dial 11. Thus where it is desired to bring a station 40 in at three o'clock the member 70 (Fig. 1) which is adjacent the numeral "3" on the dial 11, is rocked to the proper position. One of the movable contacts 60 to 63a engages the arm 13 shortly before the beginning of the selected fifteen minute 45 period and remains in contact for a short time after. At exactly the beginning of this period the timer makes contact and energizes the proper solenoid. If the adjacent element 70b is also set on the same station, the same solenoid will be 50 energized since this operates on a switch 99a to 99d which is already in. Thus, if it is desired to maintain the station in for one hour or longer, a corresponding number of the members 70 will be set in series for that purpose.

The belt 12a has one portion always movable in close association with the face of the dial 11 so that the slit 48, 48a or 48b will be passing over the dial in synchronism with the clock mechanism for indicating the time of the day. Since 60 the dial 11 shows the hours from 1 to 12, inclusive, two slits 48 and 48a are provided in the belt 12a and these slits are located at 180° apart so that when one slit moves away from the dial 11 the other slit will appear. Thus it will be seen 65 that the operator of the radio can readily set said radio to bring in any predetermined station at a definite time by an inspection of the dial 11 and one of the slits 48 or 48a through which a light shines and these rays also pass through the trans- 70 parent dial 11.

In the event that the slit 48 does not properly align with one of the indicators on the dial, as where the current has been cut off accidentally, the knob 38 is pushed inwardly so that the group of 75

elements 35 and 36 will be engaged while the gear 21 is moved out of engagement with the gear 20. The knob 38 is then revolved towards the right and the belts 12 and 12a are moved through the medium of the gears 20 and 30 until the slit 49 reaches the proper indication on the dial 11 for indicating the time of the day.

The knob is then released and the spring 39 will force the knob and the shaft 22 outwardly whereby the gear 21 will be forced into mesh with the gears 23 and 20 and the belts will then be moved.

Each one of the arms 73 when properly set will be engaged by one of the respective spring contacts 60 to 63, inclusive, slightly before the time for operating one of the respective magnets 90 to 93, inclusive, and the respective solenoids 90a to 93a but the circuit to a solenoid or magnet is not closed because the cam member 42 will retain the spring arm upwardly and therefore the contacts 53 and 54 will be open because the member 53 is riding on the cam 42. When the member 53 slides off the cam member 42 a circuit will be closed through the contacts 53 and 54 and arms 71 and 25 one of the spring members 60 to 63, inclusive. The current will then pass through the proper brush 83 to 86, inclusive, for placing one of the magnets 90 to 93, inclusive, in operation.

The cam member 41 is continuously revolved by the gear 30 and makes a complete revolution every fifteen minutes so that the current will be cut on and off at each fifteen minute period.

In the event that the cam member does not open or close the circuit directly at the end of each period, the knob 58 in front of the panel may be revolved to change the position of the cam 42 by the medium of the shaft 56 and the intermeshing gears 55 and 43. The direction in which the knob 58 is revolved will depend upon whether 40 a cam opens and closes the switch too soon or too late.

Referring more particularly to Fig. 9, it will be seen that the switch 115 must be closed in order that current will pass through the wires 94 and 95 to the respective contacts 51, 54, the shaft 75 as well as the arm 73. One of the switch members 60 to 63, inclusive, and the respective wires connect the contacts 83 to 86, inclusive, with one of the respective magnets 90 to 93, inclusive.

When the magnet 91 is energized the switch 120 will be closed and current from the wires 88 and 88a will pass through the solenoid 90a and the armature of this solenoid will act upon the member 99a, bridging the contacts 126, and these contacts, as has been stated, are connected with the usual operating mechanism (not shown) which tunes in a station automatically.

It is to be borne in mind that current flows through magnet 90 and solenoid 90a for only a brief period at each fifteen-minute interval.

Any one of the buttons B1 to B4, inclusive, may be operated manually to bring in a station when desired. However, where several stations have been set at different intervals of time, the current to the various solenoids which controls the tuning in of such stations will be cut on automatically. Springs 96a simply restore the solenoid armatures to normal position.

This type of mechanism is common to radios where automatic tuning is employed and it is believed that no description is necessary.

On the other hand where it is desired to maintain the radio off for a certain period of time one of the discs 70 is so set that it will engage the spring contact 63a on the belt 12. When this

happens the solenoid 99a is energized and the member 99 will be moved out of engagement with the contacts 128. However, the magnet 89 will first be energized to close the switch 119 so that the circuit to the solenoid 99a will be closed and this circuit includes the wires 88 and 88a. The contacts 123 are connected to the radio circuit and since the switch 99 has been opened by the energizing of the solenoid 99a against the tension of the spring 127, the radio will remain inoperative.

When the device is made a part of the set, no switch other than switch 99 would be necessary for turning the radio off or on. In order to turn the radio on manually, one of the buttons B' to B⁴ inclusive must be pushed in when the switch 99 will snap out and close the circuit to the radio and the selected station will be tuned in when the correct operating disks have been set.

Referring more particularly to Fig. 11 it will be seen that a modified form of the arrangement 20 illustrated in Fig. 9 is provided and instead of the timing mechanism being embodied in the radio as a unit, as has been described in connection with Fig. 9, the timing mechanism and all of the operating parts are enclosed in a separate housing 130 and this housing is adapted to be moved in close association with the front panel 10b of the radio having automatic tuning so that plungers 131 to 134, inclusive, may be aligned with the usual push buttons 135 to 138, inclusive, and the housing 30 then is secured in any approved manner in operative relation of the front panel of the radio so that when the knobs 139 to 142, inclusive, are operated the members 131 to 134 which are associated with knobs 135 to 138 are forced inwardly 35 for automatically tuning in a predetermined station.

All those parts which are common to the system shown in Fig. 9 will have the same numerals except the solenoids 143 to 146, inclusive. However, the wires 94 and 95 which are connected to the low energy current of the radio are all combined in a cable. Provision must be made for connecting these wires to the proper circuit in the radio as has been explained in connection with Fig. 9. Wires 88 and 88a are also included in a cable together with the various branch wires. Provision must be made for connecting the ends of these wires to the high energy current of the radio. For this purpose the usual plug-in sockets are used.

In this type of device, a pair of magnets 150 and 151 are installed within the housing 130 for operating a switch 152 for bridging a pair of contacts 153 and 154 which are connected to the usual radio supply as represented by the wires 155 and 156. These wires form part of the circuit which is connected to the house current and the switch 152 in this event will take the place of the ordinary switch for turning on or off the radio.

A magnet 160 operates a switch 161 which is adapted to engage a contact 162. The contact 162 is connected by a wire 163 with the magnet 150 and a wire 164 leads from this magnet to the negative side of the radio.

A wire 165 connects the switch 161 with the wire 88.

The wire 166 connects the magnet 160 with the wire 88a while a wire 169 connects the contact 88a with the magnet 160.

The magnets 90 to 93, inclusive, together with their respective switches 120 to 123 operate in a similar manner to the magnets and the switches shown in Fig. 9 and the wiring connections are identical.

When it is desired to tune in a station a knob (not shown) for operating the switch 152 is actuated for moving the switch 152 so that the usual house current completes the circuit to the radio. Any one of the knobs 139 to 142 may be pushed inwardly to operate one of the buttons 135 to 138, inclusive, and the proper discs 70 are then moved to bring in the desired station and the number of discs operated will determine the period of time that the station will be maintained in operation.

When it is desired to have the radio remain idle for a period of time it is only necessary to rock one of the members 70 so that the arm 173 will engage the movable contacts 63a. When this happens the relay or magnet 160 will be energized so that current will pass through the wires 163 and 164 whereby the relay 150 will be energized and the switch 152 will be opened. The timer, however, continues to operate every fifteen minutes but as long as the arm 173 is engaged by the movable contact 63a then no stations will come in.

When, however, certain of the discs 70 are set for bringing in a station and one of the buttons 139 to 142 is pushed inwardly, the relay 151 will be brought into play, since the various contacts 170 associated with the contacts 171 are simultaneously closed by one of the switches 120 to 123 and the switch 152 is closed for controlling the main circuit of the radio connected with the house current.

Referring more particularly to Fig. 8, it will be seen that the timer may be advanced immediately after the contacts close due to the particular construction of the member 53a and the free end 42a of the cam 42. If it be found that the mechanism is changing stations after the actual change in program occurs, then the member 43 is rotated in the same direction as the direction of rotation of the cam and assumes the position shown in Fig. 8. On the next revolution the contacts will close earlier.

It will be appreciated that instead of one cam, as shown, a number of cams may be employed on the same ring and spaced at equal distances apart. Thus it will be seen that where two cams are employed, these cams will be located 180° apart.

We claim:

1. An automatic tuning device for radios comprising an endless belt, means for operating the belt, spaced conductors carried by the belt, a brush for each conductor, a plurality of solenoids, means electrically connecting each solenoid with a corresponding brush, a wire connecting each solenoid with one side of a line of an electric current source, a spring finger connected to each conductor, a plurality of juxtaposed rockable discs, each disc having a contact arm, one or more of the arms adapted to be moved into the path of one of the spring fingers when the connected discs are rocked, a time controlled switch, means for opening and closing the switch periodically, means electrically connecting one element of the switch with the discs, and means connecting the other element of the switch with the source of current to complete the circuit.

2. An automatic tuning device for radios comprising an endless belt, means for operating the belt, spaced conductors carried by the belt, a brush for each conductor, a plurality of solenoids, means electrically connecting each solenoid with a corresponding brush, a wire connecting each solenoid with one side of a line of an electric current source,

a spring finger connected to each conductor, a plurality of juxtaposed rockable discs, each disc having a contact arm, one or more of the arms adapted to be moved into the path of one of the spring fingers when the connected discs are rocked, a time controlled switch, means for opening and closing the switch periodically, means electrically connecting one element of the switch with the discs, means connecting the other element of the switch with the source of current to complete the circuit, and means for properly positioning the switch relative to the opening and closing means for the switch.

3. An automatic tuning device for radios comprising an endless belt, means for operating the belt, spaced conductors carried by the belt, a brush for each conductor, a plurality of solenoids, means electrically connecting each solenoid with a corresponding brush, a wire connecting each solenoid with one side of a line of an electric current source, a spring finger connected to each conductor, a plurality of juxtaposed rockable discs, each disc having a contact arm, one or more of the arms adapted to be moved into the path of one of the spring fingers when the connected discs are rocked, a time controlled switch, means for opening and closing the switch periodically, means electrically connecting one element of the switch with the discs, means connecting the other element of the switch with the source of current to complete the circuit, a second endless belt driven by the operating means for the first belt, an elongated clock dial associated with the second belt and means on the second belt and movable over the dial for indicating the time of day.

4. An automatic tuning device for radios comprising an endless belt, means for operating the belt, spaced conductors carried by the belt, a brush for each conductor, a plurality of solenoids, means electrically connecting each solenoid with a corresponding brush, a wire connecting each solenoid with one side of a line of an electric current source, a spring finger connected to each conductor, a plurality of juxtaposed rockable discs, each disc having a contact arm, one or more of the arms adapted to be moved into the path of one of the spring fingers when the connected discs are rocked, a time controlled switch, means for opening and closing the switch periodically, means electrically connecting one element of the switch with the discs, means connecting the other element of the switch with the source of current to complete the circuit, a second endless belt driven by the operating means for the first belt, an elongated clock dial associated with the second belt and means on the second belt and movable over the dial for indicating the time of day, the dial having graduations representing periods of a predetermined number of minutes, there being a disc for each graduation.

5. An automatic tuning device for radios comprising an endless belt, means for operating the belt, spaced conductors carried by the belt, a brush for each conductor, a plurality of solenoids, means electrically connecting each solenoid with a corresponding brush, a wire connecting each solenoid with one side of a line of an electric current source, a spring finger connected to each conductor, a plurality of juxtaposed rockable discs, each disc having a contact arm, one or more of the arms adapted to be moved into the path of one of the spring fingers when the connected discs are rocked, a time controlled switch, means for opening and closing the switch periodically, means electrically connecting one element of the switch with the discs, means connecting the other element of the switch with the source of current to complete the circuit, a second endless belt driven by the operating means for the first belt, an elongated clock dial associated with the second belt and means on the second belt and movable over the dial for indicating the time of day, the dial having graduations representing periods of a predetermined number of minutes, there being a disc for each graduation.

- switch with the discs, means connecting the other element of the switch with the source of current to complete the circuit, a second endless belt driven by the operating means for the first belt, 5 an elongated clock dial associated with the second belt and means on the second belt and movable over the dial for indicating the time of day, means for manually moving the second belt independently of the operating means for properly 10 positioning the indicating means on the second belt relative to a particular graduation on the dial.
6. An automatic tuning device for radios comprising an endless belt, means for operating the belt, spaced conductors carried by the belt, a brush for each conductor, a plurality of solenoids, means electrically connecting each solenoid with a corresponding brush, a wire connecting each solenoid with one side of a line of an electric current source, a spring finger connected to each conductor, a plurality of juxtaposed rockable discs, each disc having a contact arm, one or more of the arms adapted to be moved into the path of one of the spring fingers when the connected discs are rocked, a time controlled switch, means for opening and closing the switch periodically, means electrically connecting one element of the switch with the discs, means connecting the other element of the switch with the source 20 of current to complete the circuit, a second endless belt driven by the operating means for the first belt, an elongated dial having graduations indicating periods of time and associated with the second belt, indicating means on the second belt 25 adapted to align successively with the graduations to designate the time of day, there being a disc for each graduation.
7. An automatic tuning device for radios comprising an endless belt, means for operating the belt, spaced conductors carried by the belt, a brush for each conductor, a plurality of solenoids, means electrically connecting each solenoid with a corresponding brush, a wire connecting each solenoid with one side of a line of an electric current source, a spring finger connected to each conductor, a plurality of juxtaposed rockable discs, each disc having a contact arm, one or more of the arms adapted to be moved into the path of one of the spring fingers when the connected discs are rocked, a time controlled switch, means for opening and closing the switch periodically, means electrically connecting one element 30 of the switch with the discs, means connecting the other element of the switch with the source of current to complete the circuit, a second endless belt driven by the operating means for the first belt, an elongated dial having graduations indicating periods of time and associated with the second belt, indicating means on the second belt 35 adapted to align successively with the graduations to designate the time of day, there being a disc for each graduation.

actions to designate the time of day, there being a dial for each graduation, and means for manually moving the second belt to properly position the indicating means for designating the time of day.

8. An automatic tuning device for radios comprising an endless belt, means for operating the belt, spaced conductors carried by the belt, a brush for each conductor, a plurality of solenoids, means electrically connecting each solenoid with a corresponding brush, a wire connecting each solenoid with one side of a line of an electric current source, a spring finger connected to each conductor, a plurality of juxtaposed rockable discs, each disc having a contact arm, one or more of the arms adapted to be moved into the path of one of the spring fingers when the connected discs are rocked, a time controlled switch, means for opening and closing the switch periodically, means electrically connecting one element of the switch with the discs, means connecting the other element of the switch with the source of current to complete the circuit, a second endless belt driven by the operating means for the first belt, an elongated clock dial having graduations indicating uniformly fractions of the hour, there being a disc for each fraction, the second belt having spaced slits through which the graduations appear, one slit moving over the face of the dial at one time and disclosing the time of the day.
